UNITED STATES PATENT OFFICE.

HANS GERDIEN, OF BERLIN-SCHMARGENDORF, AND MARCELLO VON PIRANI, OF BERLIN-WILMERSDORF, GERMANY, ASSIGNEES TO SIEMENS & HALSKE A.-G., OF BERLIN, GERMANY, A CORPORATION OF GERMANY.

ELECTRICAL INCANDESCENT LAMP.

1,139,668.

Specification of Letters Patent. Patented May 18, 1915.

Application filed February 16, 1915. Serial No. 8,626.

To all whom it may concern:

Be it known that we, HANS GERDIEN, a German citizen, and resident of Berlin-Schmargendorf, Germany, and MARCELLO VON PIRANI, an Italian citizen, and resident of Berlin-Wilmersdorf, Germany, have invented certain new and useful Improvements in Electrical Incandescent Lamps, of which the following is a specification.

10 This invention relates in general to an electric lamp with a gas filling and an incandescent filament. The filling more particularly may consist of any proper gas, or mixture of gases, for instance mercury vapor mixed with other gases such as argon or nitrogen. In an incandescent lamp of this latter kind the mercury vapor will be generated in the well known manner by the heat radiating from the filament which is 15 20 preferably made in concentrated form such as in the form of a spiral.

Our present invention in brief consists therein that we arrange a separating wall or similar device preferably above or around 25 the filament of the lamp for the purpose of providing a chamber or space around the filament which space is more or less separated from the remaining space within the bulb. This separating wall moreover is so 30 constructed that it will not result in an absolutely tight separation between the two spaces in the lamp bulb, but in such a manner that it will permit an exchange of the gases between said spaces only to a limited 35 extent. For this purpose the separating wall may be provided with slots or holes enabling the passage of gas from one into the other space. Our incandescent lamp by reason of the employment of the aforementioned 40 spaces will operate in such a manner that the ascending or upward whirling of gas, for instance of the hot mercury vapor which is generated by evaporation, will be prevented. Thus in case mercury is employed, in the 45 50 lower space or chamber for the filament an atmosphere will be generated which consists mainly of pure mercury vapors, while the other gas which is possibly present will be pushed into the upper space of the bulb; in this manner the mercury vapor will essentially be kept within the lower space. In the incandescent lamp according to our present invention the separating wall or similar device will also be heated by the filament,

so that in case mercury vapor is employed 55 as filling, there will only little quantities of mercury be able to condense upon said wall. By this arrangement it will also be prevented that mercury after being condensed will fall down in drops upon the 60 filament.

The advantages which are secured by our present invention consist mainly therein that the filament will burn in a relatively quiet and rather pure atmosphere of mercury 65 vapor. Since mercury vapor is a much poorer conductor of heat and electricity than other indifferent gases, for instance nitrogen, argon, etc., the filament in our present incandescent lamp can therefore be 70 much better utilized than has heretofore been possible.

The employment of the separating wall or similar device which we have so far described, is not limited to lamps containing a 75 filling of mercury vapor. In particular we have found that this arrangement is also of great importance, if no mercury at all is contained in the filling, that is if the same consists of a gas or gases other than mercury 80 vapor. In this case by said separating wall or similar device an economizing effect is secured similar to that in the so-called economizing arc lamps.

Our invention will be more fully understood by reference to the accompanying drawing which shows two forms of lamps according to our invention, and of which—

Figure 1 shows an incandescent lamp with mercury vapor as a filling which is provided 90 with the aforementioned separating wall, and Fig. 2 is a modification of the lamp of Fig. 1; which modification consists mainly therein that the filling contains no mercury and that the separating wall of Fig. 1 is so 95 constructed that it will act as economizing device as above mentioned.

In the drawing *a* represents the incandescent filament which is preferably made from metal and which is wound up in the 100 manner of a spiral, *b* is the bulb of the lamp, *c* the mercury contained therein and *d* the separating wall which is arranged above the filament.

In order to establish a communication between the space above the separating wall and that below the same, this wall may for instance be provided with openings which

are arranged at or near the point of passage of the leading-in wires carrying the filament or near the bulb, so that an exchange of gases will be enabled to a certain extent between said two spaces. The separating wall *d* moreover is mounted above the filament and so closely thereto that it will be heated by the same.

In Fig. 2 the separating wall *d* of Fig. 1 is replaced by the economizing device *d*₁ which may either be of the form of a plate or of an inverted bowl, as shown in the drawing. In addition to this economizing device a further plate *e* may be employed below the filament which may be of transparent material such as quartz-glass, mica or a similar substance. The incandescent filament will therefore be fully surrounded by a chamber which is formed by the wall *d*₁ and the plate *e*. In the same manner as in Fig. 1 holes *f* may be provided at proper points, for instance as indicated in the drawing for permitting a limited exchange of gases between the space of the filament and the remaining part of the glass bulb.

Having thus described our invention we claim as new and desire to secure by Letters Patent of the United States:—

1. In an electric incandescent lamp the combination of a bulb, a gas filling, a filament mounted within said bulb, and a separating wall mounted near said filament and dividing the interior of said bulb into two spaces, said wall being adapted to permit a limited exchange of gas between said spaces.

2. In an electric incandescent lamp the combination of a bulb, a gas filling, a filament mounted within said bulb, an economizing device partly or wholly surrounding said filament, said economizing device forming a space or chamber around said filament and being adapted to permit a limited exchange of gas between said space or chamber and the remaining part of the space within said bulb. 40

3. In an electric incandescent lamp the combination of a bulb, a gas filling containing mercury, a filament mounted within said bulb, and a separating wall mounted above said filament and dividing the interior of said bulb into two spaces, said wall being adapted to permit a limited exchange of gas between said spaces. 45

4. In an electric incandescent lamp the combination of a bulb, a gas filling containing mercury, a filament mounted within said bulb, and a separating wall mounted above said filament and having openings whereby a limited exchange of gas will be permitted between the two spaces which are formed 50 by said separating wall. 55

In testimony whereof we have hereunto set our signatures in, the presence of two subscribing witnesses.

HANS GERDIEN.
MARCELLO VON PIRANI.
